UNITED STATES PATENT OFFICE.

JOSEPH W. MAYER, OF TROY, NEW YORK, ASSIGNOR TO JOHN A. MURRAY, OF ALBANY, NEW YORK.

MOUTHPIECE FOR BRUSH-MAKING MACHINES.

1,349,845.

Specification of Letters Patent.

Patented Aug. 17, 1920.

Application filed February 19, 1920. Serial No. 359,892.

To all whom it may concern:

Be it known that I, JOSEPH W. MAYER, a citizen of the United States, residing at Troy, in the county of Rensselaer and State of New York, have invented new and useful Improvements in Mouthpieces for Brush-Making Machines, of which the following is a specification.

Reference may be had to the accompanying drawings, and the reference characters marked thereon, which form a part of this specification. Similar characters refer to similar parts in the several figures therein.

This invention relates to a brush-making machine in the use of which small bunches of bristles or the like are doubled and driven in connection with a wire staple, into a close-fitting aperture in a brush-back or block.

20 In such machines the bristles are embraced midway of their length by the staple and the staple and bristles are then together forced through a converging throat or mouth-piece, causing the bristles to be doubled and to leave the contracted end of the throat or mouth-piece in compact form.

The interior of such a bristle-feeding throat or mouth-piece must be quite accurately formed, and in machines adapted for 30 making the smaller brushes such as hair-brushes, the throat or mouth-piece is of such small dimensions that it is found extremely difficult to properly machine the interior of the throat so that the same shall be of accurate dimensions.

It is particularly necessary that such a throat or mouth-piece should be provided with oppositely disposed grooves very accurately formed for guiding the staple, for 40 unless the staple is accurately guided it will not be properly presented to the brush-back and will tend to buckle or bend when driven into the brush-back.

On account of this difficulty it has been 45 customary to make such a throat or mouth-piece of comparatively soft easily workable metal, as a result of which the throat or mouth-piece becomes soon worn so that the form and size of the passageway there- 50 through, and particularly the form and size of the staple-guiding grooves, are materially changed, become enlarged by wear and fail to properly guide the staples.

The principal objects of the invention are 55 to secure greater accuracy and longer period

of usefulness of such a throat or mouth-piece; and to facilitate the manufacture and repair of the same.

Other objects will appear in connection with the following description.

Figure 1 of the drawings is a view in front elevation of a metal block adapted to be formed into the body of such a throat or mouth-piece.

Fig. 2 is a view in side elevation of the 65 same.

Fig. 3 is a top plan view of the same with four holes drilled therein, the two middle holes being filled by driven-in temporary 70 plugs or pins.

Fig. 4 is a similar view showing the portion of the block and of said plugs between the two outermost bored holes chipped out to form a downwardly contracted slotted opening through the block.

Fig. 5 is a similar view of the finished 75 throat or mouth-piece showing the upper end of the slot extending through the side walls of the block and the temporary plugs replaced by grooved plugs adapted to form a staple-guide.

Fig. 6 is a view in front elevation of the finished throat or mouth-piece.

Fig. 7 is a side view of the same.

Fig. 8 is a vertical cross section of the 85 same taken on the broken line 8—8 in Fig. 7.

Fig. 9 is a horizontal section of the same taken on the broken line 9—9 in Fig. 7.

Referring to the drawings wherein the invention is shown in preferred form, the 90 mouth-piece as shown in Figs. 5 to 9 inclusive comprises a block 1, a pair of plugs or pins, 2, secured by cross-pins, 3, in apertures, extending vertically through the block.

In Figs. 1, 2, 3, and 4, I have shown the block in process of manufacture.

In making my improved mouth-piece, I employ a block of substantially the form shown in Figs. 1, 2 and 3, through which 100 block I drill two apertures, 4 and 5, convergently from the upper to the lower end of the block.

Midway between these apertures, 4 and 5, I drill two parallel apertures, 6 and 7, on 105 opposite sides of and close to a plane extending through the axes of said apertures, 4 and 5.

Into these respective apertures, 6 and 7, I drive close-fitting plugs or pins, 2. I then 110

bore and chip out by suitable tools the parts of the block and of said plugs and pins, 8 and 9, between said apertures, 4 and 5, thus forming a downwardly tapered slot, 10, leading to an outlet aperture, 11, in the lower end of the mouth-piece.

After the slot, 10, has been thus formed, I drive out the temporary pins or plugs, 2, and replace them with close-fitting permanent pins or plugs, 12, 13, which are tightly driven into the respective apertures, 6 and 7.

These permanent pins or plugs, 12, 13, are provided on their inner faces with longitudinal grooves, 14, adapted to receive and guide the oppositely disposed legs of a staple in its passage through the mouth-piece.

The permanent pins or plugs, 12, and 13, are secured in position by cross-pins, 3, inserted therethrough and through the block.

This method of constructing the mouth-piece enables me to very accurately form and locate the staple-guiding grooves, 14, as well as to insure long life for said grooves, because the pins or plugs, 12, 13, can be separately formed, grooved and hardened or tempered before they are inserted in the block, 1.

By employing the temporary pins, 2, which can be made of comparatively soft metal, I am able to facilitate the accurate formation of the slot, 10, through the block.

The apertures, 6 and 7, and 4 and 5, can be very accurately drilled by means of a suitable jig so that the apertures, 6 and 7, will be very accurately located for reception of the permanent pins or plugs, 12, 13.

Variations or irregularities in chipping through the temporary plugs or pins, 2, in forming the slot, 10, therefore become immaterial because these pins are replaced by the permanent pins or plugs, 12, 13, in which the staple-guiding grooves, 14, can be very accurately formed before the pins are inserted in the block, and the receiving apertures, 6 and 7, for said permanent pins being accurately located, the staple-guiding grooves, 14, will necessarily be very accurately located.

The permanent pins or plugs, 12, 13, can be renewed when they become worn, by first driving out the cross-pins, 3, and then driving out the pins, 12, 13, and replacing the same by new similar pins or plugs.

I am thus able not only to prolong the useful life of the mouth-piece by renewal from time to time of the pins, 12, 13, which form the staple-guiding grooves, but also to secure a high degree of accuracy in the form of the staple-guiding grooves.

The slot, 10, which serves to guide the bristles as they are driven by the staple downward through the mouth-piece may have its upper end extended through the side walls of the block as shown at 15, if desired.

The block, 1, which is of general rectangular form is machined to the finished form shown in Figs. 7 and 8, after the groove, 10, has been formed therein.

What I claim as new and desire to secure by Letters Patent is

1. A bristle-feeding mouth-piece for brush-making machines comprising an integral block provided with a downwardly tapered bristle-guiding slot therethrough, and on opposite sides of said slot drilled apertures open on the inner side to said slot, and pins tightly fitting said respective drilled apertures, said pins being cut-away on their inner sides to conform to said slot and being provided with oppositely disposed staple-guiding grooves.

2. A bristle-feeding mouth-piece for brush-making machines comprising an integral block provided with a downwardly tapered bristle-guiding slot therethrough, and on opposite sides of said slot drilled apertures open on the inner side to said slot, and pins tightly fitting said respective drilled apertures, said pins being cut-away on their inner sides to conform to said slot and being provided with oppositely disposed staple-guiding grooves, and cross-pins inserted through said block and said tight-fitting pins.

3. That improvement in the art of making mouth-pieces for brush-making machines which consists in drilling two convergent apertures from top to bottom through a suitable block, and two other parallel apertures from top to bottom through said block on opposite sides of and close to a plane extending through the axes of said convergent apertures, inserting close fitting temporary plugs or pins in said parallel apertures, cutting out the material of said block and said pins to form a downwardly tapered slot extending from one to the other of said convergent apertures, removing said temporary pins or plugs, and inserting in place thereof in said respective parallel apertures permanent plugs or pins conforming to said slot and provided on their inner faces with oppositely disposed staple-guiding grooves.

In testimony whereof, I have hereunto set my hand this 13th day of February, 1920.

JOSEPH W. MAYER.
